UNITED STATES PATENT OFFICE.

LEGRAND CROFOOT, OF SYRACUSE, NEW YORK.

DOOR-FASTENER.

Specification of Letters Patent No. 16,048, dated November 11, 1856.

To all whom it may concern:

Be it known that I, LEGRAND CROFOOT, of Syracuse, in the county of Onondaga and State of New York, have invented certain 5 new and useful Improvements in Door-Fasteners; and I do hereby declare that the following is a full and exact description thereof, reference being had to the accompanying drawing, in which—
10 Figure 1 represents the front elevation and Fig. 2, a side elevation of my improved door fastener. Figs. 3, 4, and 5 show the different views of the same contrivance when locked.
15 The object of the door fastener is to lock from the inside of the room doors, where there are no permanent locks attached to or where no reliability can be placed in the existing locks. It is therefore a portable instrument invented for the use of travelers with the view of promoting their personal safety and comfort.

To enable others skilled in the arts to use and to construct my improved door fastener I now proceed to describe its construction and its *modus operandi*. It is composed of two parts A and B, of unequal length and hinged together by a pin at *p*. The two parts are cut out of a plate of 25 suitable metal (brass for instance) in such a manner as to leave provision for the hinge, which is made of a slip or slips of the metal plate by bending and rounding it over a proper tool. The other extremity is 30 also bent, but at a right angle with the plate A or B. These, shown as *a* and *b* answer two different purposes: the first, *a* is a hook, which is intended to penetrate the wood of the door-post or case and acts as a clasp, 35 which cannot be removed, when the door is shut. The other *b* is a stop, which, when the 2 plates A and B are locked, will pre-

vent the door from being opened. The function of each of the 2 plates being now understood, it is necessary to explain the other 45 parts, which are appurtenances for the purpose of insuring infallibility and nicety in operation. The plate A is furnished on the outside with a spring bolt sliding in two mortises *m* and *m*; it is kept 50 permanently locked, or in the position shown in the annexed drawing, by a spiral spring, wound around its shank, and requires to be pulled back, in order to disengage the projecting eyehook *y* of the plate 55 B, which corresponds to a slot in the plate A. When the two plates are closed the spring bolt will be pushed back gradually until the bar of the eyehook shall have passed it, the spring will then be relieved 60 and force the bolt forward to catch the hook in the eye and keep it firmly locked until is is purposely disengaged.

The plate B may be armed with a spring 65 in order to cause its flying off, when it is disengaged by pulling back the spring bolt.

The advantages of my improved door fastener, over other, consist in the simplicity of its construction and the infallibility of 70 operation.

What I claim as my invention, and desire to secure by Letters Patent is:

Combining the two plates A and B constructed in the manner described with the 75 spring bolt of the plate A and the eyehook *y* of the plate B.

In testimony whereof I have signed my name to this specification before two subscribing witnesses.

LEGRAND CROFOOT.

Witnesses:
